(57) **CLAIM**

I claim the ornamental design for the container with thumb access, as shown and described.

DESCRIPTION

FIG. 1 is a perspective view of the container with thumb access with the door in an open position;

FIG. 2 is a perspective view similar to FIG. 1, but with the door in a closed position;

FIG. 3 is an end view of the container as shown in FIG. 1;

FIG. 4 is an end view of the container as shown in FIG. 2;

FIG. 5 is a top view of the container as shown in FIG. 1;

FIG. 6 is a side view of the container as shown in FIG. 1;

FIG. 7 is a top view of the container as shown in FIG. 2; and,

FIG. 8 is a side view of the container as shown in FIG. 2.
